(57) **CLAIM**

The ornamental design for a fastener for steel cable conveyor belts, as shown and described.

DESCRIPTION

FIG. 1 is a perspective view of a fastener for steel cable conveyor belts, showing my new design;

FIG. 2 is a front end elevational view thereof;

FIG. 3 is a rear end elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an end elevational view thereof wherein the set screws have been removed, the other end elevational view being identical.

The dashed broken lines show portions of the fastener for steel cable conveyor belts that form no part of the claimed design.
